[57] **CLAIM**

The ornamental design for a sandwich container or the like, as shown and described.

DESCRIPTION

FIG. 1 is a perspective view of a sandwich container or the like showing my new design;

FIG. 2 is a left side elevation thereof; the right side elevation being a mirror image thereof;

FIG. 3 is a top plan view thereof;

FIG. 4 is a front elevation thereof;

FIG. 5 is a rear elevation thereof; and

FIG. 6 is a bottom plan view thereof.
